(57) **CLAIM**

The ornamental design for a wheel for a vehicle, as shown and described.

DESCRIPTION

FIG. 1 is a perspective view of a of a wheel for a vehicle, showing our new design;

FIG. 2 is a second perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The diluted toned portions shown in FIGS. 1-8 of the drawings depict portions of the wheel for a vehicle that form no part of the claimed design. The grayscale shading of the drawings depict the shape of the three-dimensional surface and do not represent any particular colors.
